Primary Examiner — Marianne Pandozzi(74) *Attorney, Agent, or Firm* — Schiff Hardin LLP**CLAIM**

The ornamental design for a vessel, as shown and described.

DESCRIPTION

FIG. 1 is a front elevational view of one embodiment of a vessel showing my new design;

FIG. 2 is a rear elevational view of the vessel shown in FIG. 1; FIG. 3 is a left side elevational view of the vessel shown in FIG. 1;

FIG. 4 is a right side elevational view of the vessel shown in FIG. 1;

FIG. 5 is a bottom plan view of the vessel shown in FIG. 1; and,

FIG. 6 is a top plan view of the vessel shown in FIG. 1. The broken lines in the drawings are included for the purpose of illustration and form no part of the claimed design.
